Fig. 2

The bottom of the floor sweeper cover, not shown, is flat and unornamented.

I claim:

The ornamental design for a floor sweeper cover or similar article, as shown and described.
